THE
TRENTON &
SACRAMENTO,
By Humphrey R. Smith
of Boston & Newark, N. J.

UNITED STATES PATENT OFFICE.

HUMPHREY R. SMITH, OF CHICAGO, ILLINOIS.

SAFETY GRIP DEVICE FOR ELEVATORS.

SPECIFICATION forming part of Letters Patent No. 530,971, dated December 18, 1894.

Application filed April 23, 1894. Serial No. 508,679. (No model.)

To all whom it may concern:

Be it known that I, HUMPHREY R. SMITH, a citizen of the United States, residing at Chicago, in the county of Cook and State of Illinois, have invented new and useful Improvements in Safety Grip Devices for Elevators, of which the following is a specification.

This invention relates to elevator apparatus and its object is to provide an improved governor controlled safety grip, simple and effective, and automatic in operation.

A further object is to provide a safety grip construction which can be operated from the car when occasion requires.

With these objects in view the invention consists in the construction, combination, location and relative arrangement of parts, as will be more fully hereinafter described, as shown in the accompanying drawings and finally pointed out in the appended claims.

In the drawings forming a part hereof Figure 1 is a bottom plan view, parts being in horizontal section of an apparatus embodying the principles of my invention. Fig. 2 is a side elevation of the construction shown in Fig. 1. Fig. 3 is a longitudinal sectional view taken on the line *y*, *y*, Fig. 1, looking in the direction of the arrows. Fig. 4 is a transverse sectional view taken on the line *x*, *x*, Fig. 1, looking in the direction of the arrows. Fig. 5 is an enlarged detail view in bottom plan. Fig. 6 is a vertical central longitudinal sectional view of the parts shown in Fig. 5, taken on the line *z*, *z*, looking in the direction of the arrows. Fig. 7 is a partial detail view in side elevation showing a modified form of mechanism for controlling the gripping jaws. Fig. 8 is a view similar to Fig. 2, taken from the opposite side of Fig. 1. Fig. 9 is a detail view, partially in section, the parts being broken away and parts omitted, showing the governor in the act of tripping trip latch *T*. Fig. 10 is a detailed transverse sectional view, illustrating a means for adjusting weight 18. Fig. 11 is a partial detail view, the parts being in horizontal section, illustrating the action of trip *T'*.

The same reference signs are used to designate the same parts wherever they occur throughout the several views.

Reference sign 1 designates the vertical guides, which are arranged in pairs, and ex-

tend on opposite sides throughout the length of the elevator shaft. These guides may be of any desirable shape, adapted to be gripped by the gripping jaws hereinafter described. In the form shown they comprise **T** shaped bars, the stem of the **T** portion projecting inwardly in position to be gripped by the gripping jaws when occasion requires, but it is obvious that any other form of safety guide may be employed, and the guides may be of any suitable or desirable material.

Reference sign 2 designates the floor of the car. On the under side of the car floor is secured in any suitable manner what I designate a safety plank, 7, to which are secured the safety grip, controlling, tripping and governor attachments hereinafter described. Safety plank 7 is of suitable length and thickness to solidly support the several mechanisms hereinafter referred to, and it extends across the bottom of the car and the ends thereof are grooved to receive the stem of **T** guides 1, as shown.

While I have shown, and, in practice, prefer to use a safety plank upon which are mounted and secured the several mechanisms comprising my safety grip apparatus, it will be readily understood that such plank can be dispensed with and the safety grip apparatus secured directly to the floor of the car.

Cast with or suitably secured to safety plank 7, is a solid web, *W*, one at each end thereof, arranged centrally of said plank and each extending a short distance along said plank. The outer ends of said web are provided with vertically perforated flanges, 3, 3, see Figs. 3 and 4, while the inner ends of said web are formed into wings, 4, 4, for a purpose presently to be described. A bolt, *P*, is received in the vertical perforations in flanges 3, 3, of web *W*, and forms the pivot for the gripping jaws, *J*, *J*, which are in the form of levers, pivoted intermediate their ends by means of interlocking flanges, 5, 5, 6, 6, to each other and to bolt *P*, as shown. The outer end of said lever is formed into a jaw, of extended surface and is arranged in proximity to the side of the stem of **T** guide 1. A pair of said levers being arranged at each end of the safety plank, constitute a pair of gripping jaws adapted, when occasion requires, to grip the guides, and arrest the movement of the

car, as will more fully hereinafter appear. The rear ends of gripping jaw levers J, J, extend parallel with flanges 4, 4, of web W, and interposed between each lever J and the face 5 of each flange 4 of said web is a set of strong spiral springs S, the tendency of which is to separate the rear ends of said levers, and thus cause the front or gripping ends to grasp the T flange of guide 1. By this arrangement it 10 will be seen that the rear end of each gripping lever is acted on by two sets of springs, and in practice I prefer to employ two spiral springs in each set, constituting a double coil, as indicated in dotted lines in Fig. 2, thus 15 producing an exceedingly effective construction whereby a strong grip on the guide rails is effected.

I will now describe the mechanism for holding the gripping jaws open, and springs S, 20 compressed. B designates a short rock shaft passing through a perforation in the floor 2 of the car and, safety plank 7, centrally of the length of the latter. Upon this shaft, and adapted to turn therewith is a cam shaped 25 block C, and also the hub of an arm A. A suitable washer or block 8^a, may be interposed between the under surface of the safety plank and the top surface of the hub of arm A, in order to offset cam C sufficiently to bring the 30 said cam approximately in line with the extreme rearwardly projecting ends of gripping jaws J, as shown, for a purpose presently to be explained. Suitably pivoted to the under surface of plank 7 is a trip latch T, having a 35 hooked toe, adapted to engage and hold the end of lever A, in a position to retain springs S compressed, and consequently gripping jaws J, J, open through the following described apparatus: Pivoted to each web W 40 is a pair of levers L. To each lever L intermediate the ends thereof is pivoted a link 8, and each link 8 is pivoted, in turn, to the inner end of a jaw J. The inner end of each lever L is connected by means of a link 10, 45 to the end of a rod R, thus constituting a toggle arrangement, so that when rods R are moved endwise the inner ends of each pair of jaws J, J, are simultaneously moved toward or away from each other. The object of this 50 arrangement is to hold the gripping jaws open by drawing the inner ends thereof together, thus compressing the springs S, by moving rods R longitudinally toward the end of the safety plank. The rods R are held 55 in position to secure the compression of the springs S by arm A and trip latch T through the mechanism now to be described.

The inner end of one of the rods R is slotted, as indicated at 11, and at its extreme inner 60 end carries a pin or projection which, as in the construction shown, may be, and preferably is, a friction roller, D. The inner end of the rod R extending from the opposite pair of jaws is bent, as shown at 12, to clear the 65 extreme inner end of the slotted rod, and its inner end is received in the said slot 11, and it carries a similar pin, projection or friction

roller D'. By this construction it will be seen that each rod R serves to guide the other in its longitudinal movement. Friction rollers 70 D, D' are arranged on diametrically opposite sides of cam plate C, for a purpose presently to be explained.

I will now describe the construction and operation of the governor whereby the trip 75 latch T is operated to release the end of lever A, in order to permit the springs S to act upon the rear ends of gripping jaw levers J and cause said gripping jaws to grip guide 1.

Journalized to a suitable stud or pin on the 80 under side of safety plank 7, or, in case no safety plank is provided, to the under side of the car floor, is the ordinary governor G, around which leads a cable E for operating the same. Said cable is also led around suitable guide pulleys, I, I. The cable E, guide pulleys I, I, and the governor G are arranged in the usual manner, the cable being stationary and revolving the governor as the car travels up and down in the elevator shaft. 85 Pivoted in or to the governor disk G, is a dog K. A light spring H may be employed to retain the dog within the governor disk, but when the governor disk is rapidly rotated, as when the lifting cable of the car breaks, and 90 the car begins to fall to the bottom of the shaft, the end or toe of dog K is forced by centrifugal action beyond the periphery of the governor disk G and in position to strike a projection M, see Fig. 2, on trip latch T, and 95 thus trip the same and release the end of arm A, when through the action of the springs S, the gripping jaws, J, J, grip guides I, and arrest the fall of the car.

I shall designate generically the mechanism for tripping the trip-latch as the tripping mechanism.

Shaft B is extended up flush with the top 105 side of the car floor, and its end may be squared or a squared socket may be provided 110 therein adapted to be engaged by a suitable wrench, which may be carried in the car as will be readily understood by reference to Fig. 2. The object of this arrangement is to permit the conductor to ease the car down 115 to a landing by suitably manipulating shaft B, in case the fall of the car is arrested by the automatic tripping and gripping devices above described between the landings. It 120 will be seen that this object is accomplished 125 by suitably manipulating shaft B through rods R and the toggle links connecting the same to the inner ends of gripping jaw levers J, J, whereby the inner ends of each pair of gripping jaws may be simultaneously drawn 130 together against the action of springs S. This I consider an important feature of my invention, as thereby the car is enabled to be expeditiously brought to a landing and the frightened passengers unloaded therefrom.

It frequently happens that serious and often fatal accidents occur in elevators, without the breaking of the hoisting ropes or cables, by the conductor losing control of his car, as

when the valve mechanism gets out of order or fails to operate properly, causing the car to descend rapidly, frightening the passengers who, seeing the car is out of control, seek to escape by jumping from the rapidly descending car. In order to provide against such a contingency I provide trip latch T with an arm 15, see Fig. 1, to which I pivot a lever, 16, which may extend in any suitable way into the car, and in position to be convenient to the conductor. By this arrangement the gripping mechanism may be operated from the car by the conductor in case the governor fails to act properly, or in case he loses control of his car. By manipulating the lever 16, the gripping mechanism may be operated independently of the governor.

In Fig. 7 I have shown a modified form which, in many cases I prefer to use. In this construction I dispense with the use of cam C, and in place thereof I provide a horizontally arranged short shaft 17, upon which is mounted a sleeve having arms projecting in opposite directions. To each arm is pivoted a rod R'. Arm A' is held in the trip latch T', so as to swing vertically when released, instead of horizontally, as in the construction above described. A weight, 18, adjustable in any suitable way as by sliding the same along arm A' may be provided to overcome the friction of the link connections of rods R' to the sleeve on shaft or stud 17, so that when the end of said arm is released from trip latch T', the entire power of the compressed springs S is applied to jaws J, J.

A chain or other suitable connection, 20, may be secured to the end of arm A' and lead into the car in order to afford a convenient way to reset the trip latch. By suitably manipulating chain 20, jaws J, J, after being set to grip the guides 1, can be relieved whereby the car can be eased down to a landing when its motion is arrested between the landings, as will be readily understood.

In practice I prefer to apply the entire gripping, controlling and governing mechanisms to safety plank 7, and then secure said plank to the bottom of the car. This arrangement possesses advantages and is convenient in handling and in transportation, but, as above explained, it may be an object to reduce weight, or for other reasons it may be desirable to dispense with the use of said plank. In such case the mechanisms above described may be applied directly to the floor of the car.

While I have shown and described in detail a specific form of apparatus for carrying out the principles of my invention, I desire it to be understood that I do not limit myself thereto, as many changes and variations would readily suggest themselves to one skilled in the art, without departing from the spirit or scope of my invention.

Having now fully described the principles of my invention and a form of apparatus embodying the same, what I claim as my own

invention, and desire to secure by Letters Patent of the United States, is—

1. In an elevator apparatus gripping jaws, a trip latch for holding the same in open position, a governor for automatically releasing said trip latch, and auxiliary means independent of the governor for releasing said trip latch; as and for the purpose set forth. 70

2. In an elevator apparatus, pivoted gripping jaws, means for holding said gripping jaws in open position, a governor for automatically releasing said holding means to set said jaws, and means for temporarily rocking said jaws about their pivots, thereby relieving said jaws; as and for the purpose set forth. 75 80

3. In an elevator apparatus, gripping jaws, means for holding the same in open position, a governor for automatically releasing said holding means to set said jaws, and means, operated from the car, for rocking said jaws about their pivots, thereby temporarily releasing the jaws after they are set, whereby the car can be eased down to a landing; as and for the purpose set forth. 85 90

4. In an elevator apparatus, gripping jaws, means for holding said jaws in open position against a spring pressure, a governor for automatically releasing said holding means to set said jaws, in combination with an auxiliary means independent of the governor for releasing said holding means; as and for the purpose set forth. 95

5. In an elevator apparatus, gripping jaws, a means for holding said jaws in open position, a governor for automatically tripping said holding means in combination with an auxiliary tripping mechanism, adapted to be operated from the car and independent of the governor and means, also to be operated from the car and independent of the governor and of said auxiliary tripping mechanism, for temporarily relieving said jaws after they are set; as and for the purpose set forth. 100 105

6. In an elevator apparatus, a guide, a gripping mechanism comprising a pair of pivoted jaws, springs pressing against said jaws to normally close the same against said guide, a trip latch, an arm adapted to be held by said latch, connections between said arm and jaws, whereby said springs are compressed and said jaws held in open position, and a governor for automatically tripping said latch, to release said lever; as and for the purpose set forth. 110 115 120

7. In an elevator apparatus, a guide, a pair of pivoted gripping jaws, springs normally adapted to press said jaws against said guide, a trip latch, an arm adapted to be held by said latch, connections between said arm and jaws comprising a system of toggle levers, and a governor for automatically tripping said trip latch; as and for the purpose set forth. 125

8. In an elevator apparatus, a pair of guides, a pair of jaws adapted to grip each guide, springs adapted to act on said jaws, a trip latch, an arm adapted to be held thereby, a

system of levers adapted to simultaneously set said jaws, connections between said arm and levers and a governor for automatically tripping said arm; as and for the purpose set forth.

9. In an elevator apparatus, guides, jaws adapted to grip the same, springs engaging said jaws normally tending to close the same, a trip latch, an arm adapted to be engaged thereby and to hold said jaws against the action of the springs, a governor for automatically tripping said latch, and auxiliary means independent of said governor for tripping said latch, operated from the car, comprising an arm connected to said latch and a lever connected to said arm and extending into the car; as and for the purpose set forth.

10. In an elevator apparatus, a gripping mechanism, a tripping mechanism for automatically setting the same, and means, independent of the tripping mechanism, for temporarily releasing said gripping mechanism, comprising a rock shaft arranged to extend into and adapted to be operated from the car, and connections between said shaft and said gripping mechanism for operating the latter from the former; as and for the purpose set forth.

11. In an elevator apparatus, gripping jaws comprising pivoted levers, arranged in pairs, springs adapted to press against said jaws to normally close the same, a tripping mechanism for automatically setting said jaws, and means operated from the car for temporarily releasing said jaws after being set comprising a system of levers connected to said jaws for simultaneously moving the same, a shaft leading into the car and connections between said shaft and levers; as and for the purpose set forth.

12. In an elevator apparatus a gripping mechanism, a tripping mechanism for automatically operating the same, comprising a speed governor a safety plank for supporting

said mechanism and governor, said plank adapted to be secured to the floor of an elevator car; as and for the purpose set forth.

13. In an elevator apparatus a safety plank adapted to be secured to the floor of an elevator car, gripping devices carried at each end of said plank, a tripping mechanism for setting said tripping devices, comprising a speed governor, also carried by said plank, and guides arranged in the elevator shaft in proximity to the ends of said plank, adapted to be gripped by said gripping devices when operated by the tripping mechanism; as and for the purpose set forth.

14. In an elevator apparatus a gripping mechanism comprising levers having extended gripping surfaces on their outer ends, said levers being arranged in pairs, a solid web arranged between each pair of levers, said levers being pivoted to each other and to said web, sets of springs arranged between said web and levers, arranged inside of the pivot, and normally tending to close the gripping jaws, means for retaining said jaws in their open position and means for releasing said gripping mechanism; as and for the purpose set forth.

15. In an elevator apparatus, a gripping mechanism, a tripping mechanism therefor, and means for temporarily releasing said gripping mechanism when set comprising a rock shaft having one end thereof extending into the car and flush with the floor thereof, whereby said shaft may be rocked from the car, and levers connected to said gripping mechanism and operated by said shaft; as and for the purpose set forth.

In witness whereof I have hereunto set my hand, this the 20th day of April, 1894, in the presence of two subscribing witnesses.

HUMPHREY R. SMITH.
